UNITED STATES PATENT OFFICE

WILLIAM H. HAST, OF MINNEAPOLIS, MINNESOTA, ASSIGNOR TO HAYDEN MILLER COMPANY, OF MINNEAPOLIS, MINNESOTA, A CORPORATION OF MINNESOTA

DISPENSER FOR OIL AND OTHER LIQUIDS

Application filed November 26, 1930. Serial No. 498,316.

My present invention provides an extremely simple and convenient device for dispensing liquids, the term being used in a liberal sense to include semi-liquids and all materials that will flow under pressure. Particularly, however, the present invention is designed as an improvement on the liquid dispenser disclosed and claimed in my pending application, Serial Number 488,896, filed 10 October 15, 1930 and is so designed that it is especially adapted for use in the dispensing of lubricating oils or light greases and the proper application thereof to various parts of machines, automobiles and the like that 15 require frequent or occasional lubrication.

From the above statement it, of course, follows that while the device is especially designed for dispensing lubricating oils, it is capable of various other uses such as the dispensing of condiments and the like.

In the accompanying drawings, which illustrate the present invention, like characters indicate like parts throughout the several views.

25 Referring to the drawings:

Fig. 1 is a vertical section taken axially through the complete device on the line 1—1 of Fig. 2, some parts being shown in full;

Fig. 2 is a view chiefly in horizontal section on the line 2—2 of Fig. 1, but with some parts broken away;

Fig. 3 is a detail in front elevation showing the principal parts of the mechanism for progressively ejecting the oil or fluid material from the jar-like container of the device; and

Fig. 4 is an axial section showing a modified form of discharge nozzle.

The container for the liquid material, hereinafter for convenience designated as the oil container or tank is of cylindrical form normally open at its top and is indicated by the numeral 5. Preferably, this container is made of metal but may be made of any suitable material. At its upper edge, the container 5 is provided with an externally threaded rim 6, upon which is seated a dome-like cap 7 also preferably of metal and having an outstanding flange 8 directly resting upon the rim 6. The numeral 9 indicates an

annular clamping ring that is internally threaded and screwed onto the rim 6. This clamping ring 9 has an inturned flange 10 that engages the flange 8 and firmly clamps the cap to the container.

The container 5 is provided or formed with a discharge tube 11 formed directly against one wall of the container but terminating at its lower end above the bottom of the container. This discharge tube 11 extends above the container and through one outwardly offset portion 7^a of the cap 7; and this upwardly projecting portion 11^a of said tube is preferably round in cross-section and terminates above the top of offset portion 7^a of cap, being extended through a perforation 12 therein. An extension tube 13 is detachably secured by threaded engagement to the projecting upper end of the tube extension 11^a and, as shown, is provided at its discharge end with a nozzle 14. Here it should be noted that the flange 8 and the lower part of offset portion 7^a of the cap 7 are cut away at 7^b so as to permit the clamping ring 9 to be screwed upward and off from the rim 6 without lifting the cap.

Working in the cylindrical container 5 is a piston head or follower 15 of any suitable construction, but, as shown, is made up of pressed metal plates riveted together and holding a pliable peripheral gasket 15^a of cork or the like that closely engages the interior of the container. Also it is important to note that at one place, the piston 15 and its gasket 15^a are notched or cut in to closely fit the exposed adjacent surface of the discharge tube 11 and so as to maintain a tight joint therewith as well as with the interior walls of the container. Incidentally, it will be noted that this engagement with the tube 11 holds the piston against rotation. Also it will be noted that the cap 7 is provided at its rear side or that side opposite the tube 11 with a loop-like handle 7^c.

A short countershaft 16 is journaled in ears 17 formed on the sides of the lower portion of a sleeve 7^d which is rigidly secured to the cap 7 as shown by being formed integral with the top thereof and depending therefrom. A spur pinion 18 is secured to shaft 16 and

meshes with the teeth of a stem 19 that works 5
slidably within the sleeve 7^a and, as shown, 10
has annular teeth but might have teeth otherwise 15
formed. The lower end of this stem 19 is secured to the piston 15, as shown, by 20
threaded engagement at 20. To one end of 25
the shaft 16 a ratchet wheel 21 is secured and 30
on the same end of said shaft is pivotally 35
mounted a small lever 22. A downwardly 40
spring-pressed pawl or ratchet dog 23 is pivoted 45
to lever 22 and the hook-like free end thereof 50
normally engages the teeth of ratchet wheel 21. Dog 23 has a depending arm 23^a.

Mounted for vertical movements through 55
the top of the cap 7 and through an interior 60
lug 7^e of said cap is an actuating plunger 24 65
normally yieldingly pressed upward by a 70
spring 25. In the lower end of plunger 24 is 75
a diametrical slot through which the free end 80
of lever 22 is projected. Fig. 4 shows a long 85
nozzle 14^a adapted to be substituted on the 90
projecting end of the extension tube 13 for 95
said shorter nozzle 14, shown in Fig. 1.

The nozzles 14 and 14^a are preferably of 100
rubber or somewhat flexible material so that 105
their tips will seat with tight joints against 110
bearings or the like to be lubricated. The 115
flexibility of the long nozzle 14^a will permit 120
bending thereof to reach points for lubrication 125
sometimes not accessible with a rigid 130
member.

When the container 5 is filled with material 135
assumed in this particular instance to be lubricating 140
oil or light grease, the piston 15 will 145
be at its highest elevation shown in Fig. 1. 150
Obviously, the plunger 24 can be depressed by 155
the thumb of the hand holding the handle 7^e 160
and for each depression of said plunger, the 165
ratchet dog 23, acting on ratchet wheel 21 and 170
through shaft 16 and pinion 18, will press 175
piston 15 downward or toward the bottom of 180
the container, thereby causing a definite 185
amount of oil or grease to be ejected from the 190
container through the stem 11—13 and nozzle 195
14. Of course, by repeated depressions of 200
the plunger 24, any desired amount of grease 205
may be ejected. When the piston has reached 210
a position at or close to the bottom of the 215
container and refilling is required, this may 220
be readily accomplished as follows: First, the 225
clamping ring 9 is unscrewed which permits 230
the cap 7 to be raised on the forwardly 235
projecting portion of the tubes 11^a and 13 far 240
enough to bring the piston out of the 245
container and then the cap can be rotated or 250
swung side-ways on said tube so as to carry 255
the piston from its position above the container 260
and to open the top of the container for 265
refilling with oil, grease or other material to be 270
dispensed. When the cap has been raised 275
from the container, the operator by pressing 280
upward on the arm 23^a lifts dog 23 out of 285
engagement with ratchet wheel 21 and then by 290
upward pressure may quickly move piston 295

15 and its stem 19 upward and backward to 30
initial or starting position.

After the container has been filled, the cap 35
will be again swung to position and lowered, 40
causing the piston to again enter the top 45
of the container and then the cap can be 50
again secured by the application of the 55
clamping ring 9. These operations just 60
described do not require complete separation of 65
the cap from the container, but simply the 70
removal thereof and of the piston from working 75
positions. Of course, the said cap and 80
the parts mounted thereon can be completely 85
disconnected from the container either by 90
taking off the nozzle 14 or by unscrewing the 95
extension tube 13, but for ordinary refilling 100
operations, this complete disconnection of 105
the cap is not desirable.

As a device for lubricating various different 110
parts of machines and mechanisms generally, 115
this device will be found highly efficient and 120
very convenient and, as indicated in the 125
introductory statements, the device is capable 130
of general use for the dispensing of various 135
liquids that will quite readily flow under 140
pressure including the various condiments, 145
dressings and liquid materials which it is 150
desirable to dispense in small quantities and 155
to keep all the time sanitary and free from 160
waste.

From the foregoing, it follows that the preferred 165
form of the device described is capable 170
of modification within the scope of the invention 175
herein disclosed and claimed.

What I claim is:

1. A dispensing device of the kind described comprising a container having a discharge tube extending from a point near the bottom thereof and projecting far above its top at one side, a cap detachably secured to the top of said container, the upwardly projected portion of said discharge tube being extended through one side of said cap and said cap being capable of rotary and sliding movements on said tube whereby the cap, when disconnected from said container may be raised and swung laterally on said tube, a stem slidably mounted in said cap, a piston secured to the lower end of said stem and working in said container, and a hand-operated mechanism applied on said cap and operative on said stem to impart step by step movements to said piston to cause ejection of material from said container through said discharge tube.

2. The structure defined in claim 1 in which said discharge tube has an extension section detachably connected to the fixed portion of said tube at a point above and outside of said cap when the latter is secured to said container.

3. The structure defined in claim 1 in which said piston-carrying stem has rack teeth and the operating mechanism includes a pinion engaging said rack teeth, a plunger

projecting from said cap, and a pawl and ratchet connection between said plunger and pinion.

4. The structure defined in claim 1 in which a portion of said discharge tube extends from the top downward along one side of the interior of said container to a point near the bottom of the latter, and said piston is notched so that it closely fits the inner portion of said discharge tube as well as the interior of said container.

5. The structure defined in claim 1 in which said discharge tube has an extension section detachably connected to the fixed portion of said tube at a point above and outside of said cap when the latter is secured to said container, the detachable section of said discharge tube having a detachable nozzle normally preventing said cap from being slid off from the end of the discharge tube.

6. The structure defined in claim 1 in which said container has an externally threaded rim and said cap has an outturned base flange resting on said rim, in further combination with a clamping ring having screw-threaded engagement with said threaded rim and provided with an inturned flange for clamping the flange of said cap onto said container.

30 7. The structure defined in claim 1 in which said cap has an outwardly bulged portion through which the discharge tube is passed, and said bulged portion being notched to permit said clamping ring to be unscrewed 35 and released while said cap is on said container.

8. A dispensing device of the kind described comprising a cylindrical container having a discharge tube, a portion of which 40 extends vertically along the inner portion of one side thereof, a cap detachably secured to said container, a stem slidably mounted in said cap, means mounted on said cap for imparting step by step axial movements to said 45 stem, and a piston connected to said stem and working in said container, said piston having a peripheral notch closely fitting the inwardly projected portion of said discharge tube.

In testimony whereof I affix my signature.

50 WILLIAM H. HAST.
